Alan R. Cripe, Richmond, Va., assignor to United Aircraft Corporation, East Hartford, Conn., a corporation of Delaware

Filed Jan. 13, 1966, Ser. No. 596

Term of patent 14 years

(Cl. D66—1)

FIG. 3

FIG. 4

FIG. 5

FIG. 1 is a top view of one end of a train;

FIG. 2 is a side view of the powered car, with an additional car shown articulated thereto, illustrating particularly the passenger-carrying dome portion at the head end of the car;

FIG. 3 is a side view of the opposite end;

FIG. 4 is a side view of the train; and

FIG. 5 is an end view from either direction.

The characteristic feature of my design resides in the powered dome-car at either end of the train, specifically as shown.

I claim:

The ornamental design for a train, substantially as shown and described.
